UNITED STATES PATENT OFFICE.

JOHN EDWARD THEBAUD, OF BUFFALO, NEW YORK, ASSIGNOR OF FOUR-FIFTHS TO
FRANKLIN D. BAILEY, OF BUFFALO, NEW YORK.

HEATER FOR MOTOR-VEHICLES.

1,181,939.

Specification of Letters Patent.

Patented May 2, 1916.

Application filed January 19, 1916. Serial No. 73,053.

To all whom it may concern:

Be it known that I, JOHN EDWARD THEBAUD, a citizen of the United States, residing at Buffalo, in the county of Erie and State of New York, have invented certain new and useful Improvements in Heaters for Motor-Vehicles; and I do hereby declare the following to be a full, clear, and exact description of my invention, such as will enable others skilled in the art to which it appertains to make and use the same, reference being had to the accompanying drawing, and to figures of reference marked thereon, which form part of this specification.

Like figures of reference refer to like parts.

This invention relates to heaters for motor vehicles, particularly to that class of vehicles propelled by hydro-carbon engines, which exhaust hot gases, that are available in whole or in part for heating purposes for the comfort of the occupants of said vehicles.

I have several objects in view in connection with this invention.

One object is to provide a heating apparatus to be of economical construction and at the same time be serviceable and applicable to standard makes of automobiles using hydro-carbon engines.

Another object is to divert part of the exhaust gases from the exhaust pipe, without increasing the back pressure on the engine and where possible to decrease said back pressure.

Another object is to provide means for regulating the amount of diverted gases for heating purposes, without increasing the said back pressure from that which obtains ordinarily with the use of exhaust pipe and muffler.

Another object is to provide a radiator, as part of the heating apparatus, which can easily be taken apart for cleaning purposes, without separating the radiator from the heating coil, or disturbing its fixed position in the body of the vehicle where installed.

A further object is to permit the circulation, through said radiator, of the confined air of an inclosed vehicle to be heated, while excluding dust and dirt laden air from passing through it into the large cavity of the vehicle, occupied by the passengers.

Another object is to provide a heating apparatus which will be so constructed as to avoid rattling, and also which will be free from the noise of exhausting gases.

To fulfil the above objects, I provide a heating apparatus adapted to divert part of the exhaust gases of the engine through a heating coil, inclosed by a separable, but tight box, having an apertured cover, and positioned for service, where desired, within the body of the vehicle. After the diverted gases have passed through the radiator, they are allowed to escape through an auxiliary muffler into the atmosphere. On the exhaust pipe of the engine, where the gases are diverted, I provide a valve of special construction, which permits of diverting part of said exhaust gases without materially increasing the back pressure on the engine. Means for regulating and holding the regulation of the operation of this valve, are provided, as are also means for holding the various movable parts spring-pressed together, to prevent rattling.

The heating apparatus in detail is herein-after described and is illustrated in the drawings and its operation is explained and what I claim is set forth.

In the drawings, Figure 1 is an elevation showing in outline, parts of the body of an inclosed automobile, having installed therein a heating apparatus embodying my invention, and shows parts broken away to illustrate internal features of construction.

Fig. 2 is a top plan view of the said apparatus shown in Fig. 1. Fig. 3 is a fragmental and perspective view of the separable heating box used to incase the said heating coils. Fig. 4 is a vertical end view of my diverting valve, showing the particular shape of the tongue of the said valve with its attached shaft and crank, for fixing its angular position in the current of exhaust gases.

This view is that looking in the direction of the movement of the exhaust gases, as they pass through the said valve. Fig. 5 is a perspective view of the blade of said valve, illustrating its concave spoon-shape. Fig. 6 is a section of said blade, taken on the line X—X of Fig. 5. Fig. 7 is a perspective view of the lever ratchet device used in regulating the angular position of the blade of said valve and of holding such angular position where desired. Fig. 8 is a sectional elevation of the

box shown in Fig. 3, but with the heating coil added.

In Fig. 1, 1 is the broken line outline of an inclosed automobile body with seats 2 and 3, steering post 4, front wall 5 and floor 6. 7 represents a hydro-carbon engine. 8 is the fragmental exhaust pipe, terminating in the muffler 9. 10 is the exhaust gas diverting valve, having a branch 11, positioned at an angle of about 45 degrees with the exhaust pipe 8. Through the broken hole, in the body of the valve 10, is shown the concave blade 12, fixed upon a shaft 13, passing through one end of said blade 12 and journaled in the body of the valve 10, and terminating in a crank 14. Extending from the branch 11, and in tubular connection therewith, is the piping 15, which is tubularly continuous with the heating coil 16, positioned within the separable, but closed box 17, having an apertured cover 18 thereon. This box 17, fixed in the floor 6, is shown in section, to expose the heating coil 16, and to illustrate the construction of the box 17. Depending from the cover 18 and integral therewith are the side leaves 19, (only one shown in this figure) which, with the end leaves 20 and 21, upstanding from and integral with the bottom 22, complete the four side walls of the box 17. The cover 18, with its leaves 19, is secured to the lower part of the box 17 by screws 23', adapted to engage threaded holes 23, in the top of the end leaves 20 and 21. The side leaves 19 engage grooves in the lower part of the box 17, with some suitable packing to air seal the joint at said grooves. Through the end leaf 21 pass ends of the coil 16, in tubular connection with the piping 15 and the piping 24, which terminates in the auxiliary muffler 25. Clamped upon the exhaust pipe 8, is the bracket 26. A tension spring 27 connects the crank 14 with the bracket 26 and normally holds the blade 12 up against its seat 28, to shut off communication between the coil 16 and the exhaust pipe 8. Depending from the floor 6 is a post 29 to which is journaled an L-lever 30, connected at its lower end, by the rod 31, with the crank 14. Positioned on the front wall 5, is the lever ratchet device 32, having a post 33, to which is journaled an end of a lever 34. Integral with the frame of the device 32, is the curved extension 35, having ratchet teeth 36, for engagement with the tongue 37, on the lever 34. In pivoted engagement with an extension 38, on the lever 34, is the rod 39, also in pivoted engagement with the end of the horizontal arm 40 of the L-lever 30. A compression spring 41, surrounding the lower end of the rod 39, and engaging the post plate 42 and also the arm 40, of the L-lever 30 tends to keep the lever 34 spring-pressed in position, wherever the tongue 37 engages the teeth 36, and prevents rattling.

of both the lever ratchet device 32 and the L-lever 30.

In Fig. 2, the cover 18 is broken away to show the coil 16 and the grooves 43, which engage the side leaves 19, beneath the cover 18. The full open position of the blade is shown dotted at 12', approximately at an angle of 45 degrees with the axis of the pipe 8. For this open position of the blade 12, the lever 14 takes the dotted position 14' and the spring 27 becomes extended.

In Fig. 3, the two assembled parts of the box 17 are shown in perspective; the upper part being shown broken away to expose the end leaf 20 and the grooves 43, which are lined with sheet packing 43', and which engage the side leaves 19, which are integral with the apertured cover 18. Holes 21^a in the end leaf 21 are provided for the protruding ends of the heating coil, when in place. When the screws 23' are withdrawn, and the cover 18, with its depending side leaves 19, is removed, there remains the bottom 22, with its upstanding end leaves 20 and 21, leaving open spaces above the bottom grooves 43, through which accumulated dust and dirt may be cleaned out and forced below the floor 6, of the vehicle, when positioned as shown in Fig. 1.

The sectional elevation shown in Fig. 8, of the box 17, illustrates the integral construction of the leaves 19 with the cover 18, and also shows the position of the heating coil 21^b.

In Fig. 4, the spoon-shaped end 12^a of the blade 12, is apparent, leaving the horse-shoe-shaped clearance space 12^b between the edge of the blade 12 and the inner wall of the valve 10, when opened. Through this horse-shoe-shaped clearance space 12^b, passes the undiverted remaining portion of the exhaust gases to the muffler 9. The larger this clearance space 12^b, the greater freedom have the undiverted exhaust gases, when passing the blade 12, in its open position. By having the blade 12 concave we increase its diverting capacity and we do not require so large a blade for a given capacity, as we would for a flat blade. The concave blade therefore offers less resistance to the passage of undiverted gases than a flat blade of the same diverting capacity. The spoon-shaped outline in either a flat or a concave blade, offers an advantage over any other shaped blade, as it gives a maximum of diverting surface, where the velocity of flow, of the exhaust gases, is greatest, that is, about the center of flow, therefore for a required amount of volume flow to be diverted, the spoon shaped blade presents a diverting surface to the best advantage, and results in decreasing the back pressure on the engine.

In Fig. 5, the concave surface 12^a of the blade 12 is better shown and still better in

Fig. 6. 12° is a transverse hole through the small end of the blade 12 adapted to securely receive the shaft 13.

In Fig. 7, the lever ratchet device 32 shows the teeth 36, on the portion 35, to be in the curved path of the tongue 37, of the lever 34, so that the rod 39 can be held at various positions to maintain the adjusted position of the tongue 12 of the valve 10. (See Fig. 1). Any other kind of a radiator than the box 17, with its coil 16, may be substituted therefor and any other suitable regulating means may be used.

In operation, exhaust gases are led from the engine 7, by connection not here shown, to the exhaust pipe 8, and are expelled into the atmosphere through the muffler 9. On the way to the muffler 9, the said gases pass through the body of the valve 10 and by means of the tongue 12, swung into the current of the exhaust gases, into the position 12', part of said gases are diverted and caused to run into the branch 11 and travel on through the piping 15, the coil 16, the piping 24 and the auxiliary muffler 25, into the atmosphere. As the coil 16 becomes heated, hot air from the central area of the apertured portion of the cover 18 rises and draws cooler air from the floor 6, in its vicinity, into the outer part of the apertured portion, between the border edge of the cover 18 and the said central portion. On account of the motion of the vehicle and other contributing causes, any one part of the said apertured portion, of said cover 12, may be in use for the ingress, and the remaining part of said apertured portion for the egress of air, as it passes through the box 17, in conveying off the heat radiated from the coil 16, within the otherwise closed box 17. It is thus possible to heat the interior of a closed vehicle without causing air to pass through the radiator box from the outside, and thus keep out dirt and dust laden air. In the lower portion of the lever 34, shown in Fig. 1, the tension spring 27 is allowed to pull the crank 14 into a position wherein the blade 12 closes the aperture in the partition seat 28, but when the lever 34 is in the position shown in Fig. 7, the crank 14 will occupy the dotted position 14', of Fig. 2, and the blade 12 will be swung into the position 12', in the path of the oncoming exhaust gases. It is important that the branch 11 be straight and positioned at about 45 degrees with the pipe 8, so that the diverted gases will be free to leave the main channel in as straight a path as possible. To change the direction of the path of these diverted gases after they have left the valve 10, is not of so much consequence. It has been found by experiment that to have a bent branch, instead of a straight one, like at 11 (Fig. 2) is to add resistance to the diverted gases im-

mediately after the diversion takes place and thus vitiate their initial impulse, which otherwise would give them a start and keep them going through the piping 15, the coil 16, and the muffler 25.

I do not wish to be confined to the exact structure herein shown, as certain details may be changed without departing from the spirit of my invention.

Hence I claim:

1. In a motor vehicle heater having tubular connection with the exhaust pipe of a hydro-carbon engine, diverting means in said exhaust pipe communicating with said tubular connection, said diverting means being adapted to divert hot gases from said exhaust pipe into said connection and to close off communication therewith, said diverting means comprising a Y-branch casing tubularly continuous, with said exhaust pipe, a valve seat within said casing opening into the Y-branch of said casing, a tongue member pivoted near one end of said valve seat and adapted to be swung into the current of hot gases flowing through said pipe and to close the opening in said seat, said tongue member being concave toward said Y-branch, and means for angularly positioning said tongue member.

2. In a motor vehicle heater having tubular connection with the exhaust pipe of a hydro-carbon engine, diverting means in said exhaust pipe communicating with said tubular connection, said diverting means being adapted to divert hot gases from said exhaust pipe into said connection and to close off communication therewith, said diverting means comprising a Y-branch casing tubularly continuous, with said exhaust pipe, a valve seat within said casing opening into the Y-branch of said casing, and a tongue member pivoted near one end of said valve seat and adapted to be swung into the current of hot gases flowing through said pipe and to close the opening in said seat, said tongue member being concave, the diverting surface of said tongue member being broadened near its swinging end and concaved toward said Y-branch.

3. In a motor vehicle heater having tubular connection with the exhaust pipe of a hydro-carbon engine, diverting means in said exhaust pipe communicating with said tubular connection, said diverting means being adapted to divert hot gases from said exhaust pipe into said connection and to close off communication therewith, said diverting means comprising a Y-branch casing tubularly continuous, with said exhaust pipe, a valve seat within said casing opening into the Y-branch of said casing, a spring pressed tongue member pivoted near one end of said valve seat and adapted to be swung into the current of hot gases

70

- flowing through said pipe and to close the opening in said seat, said tongue member being concave toward said Y-branch, and means for angularly positioning said tongue member.
4. In a motor vehicle heater having tubular connection with the exhaust pipe of a hydro-carbon engine, diverting means in said exhaust pipe communicating with said tubular connection, said diverting means being adapted to divert hot gases from said exhaust pipe into said connection and to close off communication therewith, said diverting means comprising a Y-branch casing tubularly continuous, with said exhaust pipe, a valve seat within said casing opening into the Y-branch of said casing, and a spring pressed tongue member pivoted near one end of said valve seat and adapted to be swung into the current of hot gases flowing through said pipe and to close the opening in said seat, said tongue member being concave, the diverting surface of said tongue member being broadened near its swinging end and concaved toward said Y-branch.
5. In a motor vehicle heater, having tubular connection with the exhaust pipe of a hydro-carbon engine, diverting means in said exhaust pipe communicating with said tubular connection, said diverting means being adapted to divert hot gases from said exhaust pipe into said connection, and to close off communication therewith, said diverting means comprising, a Y-branch casing tubularly continuous, with said exhaust pipe, a valve seat within said casing, opening into said Y-branch of said casing, a tongue member pivoted near one end of said valve seat and adapted to be swung into the current of hot gases flowing through said pipe and to close the opening in said seat, said tongue member having a diverting surface concave toward said Y-branch, and having its pivotal axis positioned between said diverting surface and the axis of the main tubular part of said casing, and means for angularly positioning said tongue.
6. In a motor vehicle heater, having tubular connection with the exhaust pipe of a hydro-carbon engine, diverting means in said exhaust pipe, communicating with said tubular connection, said diverting means being adapted to divert hot gases from said exhaust pipe into said connection, and to close off communication therewith, said diverting means comprising, a Y-branch casing tubularly continuous, with said exhaust pipe, a valve seat within said casing, opening into said Y-branch of said casing, a tongue member pivoted near one end of said valve seat and adapted to be swung into the current of hot gases flowing through said pipe and to close the opening in said seat, said tongue member having a diverting surface and the axis of the main tubular part of said casing, and means for angularly positioning said tongue.
7. In a motor vehicle heater, having tubular connection with the exhaust pipe of a hydro-carbon engine, diverting means in said exhaust pipe communicating with said tubular connection, said diverting means being adapted to divert hot gases from said exhaust pipe into said connection, and to close off communication therewith, said diverting means comprising, a Y-branch casing tubularly continuous, with said exhaust pipe, a valve seat within said casing, opening into said Y-branch of said casing, a spring pressed tongue member pivoted near one end of said valve seat and adapted to be swung into the current of hot gases flowing through said pipe and to close the opening in said seat, said tongue member having a diverting surface concave toward said Y-branch, and having its pivotal axis positioned between said diverting surface and the axis of the main tubular part of said casing, and means for angularly positioning said tongue.
8. In a motor vehicle heater, having tubular connection with the exhaust pipe of a hydro-carbon engine, diverting means in said exhaust pipe, communicating with said tubular connection, said diverting means being adapted to divert hot gases from said exhaust pipe into said connection, and to close off communication therewith, said diverting means comprising, a Y-branch tubularly continuous, with said exhaust pipe, a valve seat within said casing, opening into said Y-branch of said casing, a spring pressed tongue member pivoted near one end of said valve seat and adapted to be swung into the current of hot gases flowing through said pipe and to close the opening in said seat, said tongue member having a diverting surface broadened near its swinging end and concave toward said Y-branch, and having its pivotal axis positioned between said diverting surface and the axis of the main tubular part of said casing, and means for angularly positioning said tongue.
9. In a motor vehicle heater, having tubular connection with the exhaust pipe with a hydro-carbon engine, diverting means in said exhaust pipe, communicating with said tubular connection, said diverting means being adapted to divert hot gases from said exhaust pipe into said connection, said diverting means comprising a Y-branch casing, tubularly continuous with said exhaust pipe, there being a port within said casing, opening into the said Y-branch, a tongue member within said casing, angularly positioned to divert flowing hot gases from said pipe into the said Y-branch, said tongue member hav-

ing a concave diverting surface extending into the path of said hot gases, flowing from said pipe.

10. In a motor vehicle heater, having tubular connection with the exhaust pipe with a hydro-carbon engine, diverting means in said exhaust pipe, communicating with said tubular connection, said diverting means being adapted to divert hot gases from said 10 exhaust pipe into said connection, said diverting means comprising a Y-branch casing tubularly continuous with said exhaust pipe, there being a port within said casing, opening into the said Y-branch, said tongue member having its diverting surface concave and broadened near one end thereof, extending into the path of said hot gases, flowing from said pipe.

11. In a motor vehicle heater, having tubular connection with the exhaust pipe of 20 a hydro-carbon engine, a radiator consisting of a heater box and a heating coil positioned within said heating box, said box comprising a bottom piece, having opposite upstanding ends integral therewith, and an apertured cover having opposite depending leaves integral therewith and adapted to fit between said ends, to form therewith the sides of said box; there being afforded, upon the removal of said cover, an open end between said upstanding ends for cleaning purposes.

JOHN EDWARD THEBAUD.
